PHILIP E. YOUNG, OF FAIRHAVEN, MASSACHUSETTS, ASSIGNOR TO ACUSHNET PROCESS COMPANY, A CORPORATION OF MASSACHUSETTS.

GOLF TEE.

Application filed March 23, 1927. Serial No. 177,496.

At the present time, various forms of golf tees are on the market, but these are not entirely satisfactory, for they are either so heavy that they are a nuisance to carry around, or else they are difficult to find after use. I have found that it is possible to make a golf tee out of rubber which will adequately support the ball and at the same time will be so light that several can be carried in the pocket without being noticed, and which will be so light that it is impossible to knock it any great distance. Its size is great enough so that it cannot readily be lost. In order to adapt the tee to various golfers, I provide means whereby the height may be readily altered.

An illustrative example of a tee embodying my invention is shown in the accompanying drawing, which illustrates the same in cross section. This tee is made of molded rubber with the walls very thin. It will be noted that it has a body portion 2, a concave top 4 which preferably is formed with a radius of curvature about equal to the radius of a golf ball, and a base or bottom bead 6. I also provide one or more intermediate beads 8, so that if the golfer prefers a lower tee, the bottom portion can readily be cut off to a bead 8, in which case such bead will serve as a base bead.

The tee is exceedingly light and will collapse in the hand or pocket, but it will be found that the strain of the ball on the top 4 will be distributed evenly to the sides which are in the form of a truncated cone, 35 so the tee will hold the ball in proper position. Even if there are some inequalities in the ground on which the tee is used, the flexibility of the sides will take care of these.

As regards size, I have found it satisfactory to make the tee with a base a little over 1 inch in diameter and the side walls about one-twentieth of an inch in thickness. The concave top may be even thinner.

What I claim is:

1. A golf tee in the form of a truncated cone of rubber with side walls of a thickness about one-twentieth of the total diameter, a very thin concave top to distribute strain to the sides and a strengthening bead about 50 the base.

2. A device as specified in claim 1, further characterized by the fact that the side wall carries a circumferential bead adapted to serve as a base bead, if the lower portion is 55 removed.

PHILIP E. YOUNG.
